UNITED STATES PATENT OFFICE.

CHARLES FRANCIS JENKINS, OF WASHINGTON, DISTRICT OF COLUMBIA.

TUBE-WINDING DEVICE.

982,430.

Specification of Letters Patent. Patented Jan. 24, 1911.

Application filed October 15, 1910. Serial No. 587,176.

To all whom it may concern:

Be it known that I, CHARLES FRANCIS JENKINS, citizen of the United States, residing at Washington, in the District of Columbia, have invented certain new and useful Improvements in Tube-Winding Devices, of which the following is a specification, reference being had therein to the accompanying drawing.

10 This invention relates to machines for winding strips spirally to form tubes and involves the use of a mandrel which has little contact surface and which itself urges the forming tube longitudinally along the mandrel.

15 In the accompanying drawings, Figure 1 shows the novel portion of the machine in side elevation. Fig. 2 shows the same parts in plan with strips winding upon the mandrel. Fig. 3 is a section on the line 3—3, Fig. 4. Fig. 4 is a vertical axial section of devices seen at the left in Figs. 1 and 2. Fig. 5 is an end view looking from the right in Fig. 1, a certain smooth mandrel segment being removed. Fig. 6 is a view corresponding to Fig. 2, common winding belts being shown in position. Fig. 7 is a view analogous to Fig. 5, showing a modification. Fig. 8 is a like view showing a different

30 modification.

In these views 1 to 4, A represents a suitable frame for supporting a winding mandrel. In this frame are revolvably mounted a central shaft B and surrounding this shaft and at equal distances therefrom and from each other are several shafts C all parallel to the shaft B, and like the latter all project to the right of the frame. Upon the projecting portions of the shafts C, respectively, 35 are fixed sleeves or hollow cylinders D, each spirally grooved to form a series of sharp ridges D' analogous to screw threads. At the right, the shafts C project slightly and are revolvables in bearings in a disk E, forming one end of a drum-like segment or extension E' of the mandrel in the axis of which the shaft B rotates. This latter shaft is rotated at suitable speed by means of a worm gear F fixed to its left end by a set screw F' and actuated in any desired way, in this instance by an electric motor G bearing upon its shaft G' a worm F' in engagement with the worm gear. Alongside the worm gear is 40 an internal gear H rotating with the worm gear and shaft B and having a broad toothed internal surface with which mesh a series of

pinions H' fixed to the ends of the shafts C, respectively, so that these shafts are all rotated in the same direction at the same speed. The set of spirally grooved cylinders 45 taken together form a mandrel segment upon which strips I, usually of paper, are wound, the inner strip forming the inner layer of a tube and the outer strip breaking joints with the other and forming, as usual, an outer layer, the meeting faces of the two being secured together by glue or the like. Whatever means may be employed for winding the strips, the inner layer meets the sleeves only along numerous spiral ridges 50 and the lines of contact are continually shifted along the inner face of the strip, and as the sharp ridges of the sleeves slightly engage the surface, the rotation being in the proper direction, the forming tube is constantly urged to the right.

With the ordinary smooth cylindrical mandrel, glue often passes through the spiral crevice between the edges of the strip to the mandrel, and the slightest smearing of 55 the mandrel thereby prevents slipping, causes the paper, if thin, to tear or become crumpled, with the consequence that the work must be stopped until the mandrel has been carefully cleaned. With the present mandrel this evil is practically eliminated since a little glue upon the ridges, which by the rotation are positively freed from any given point of contact with the tube after an instant's contact, has no perceptible effect. As the formed tube advances 60 it passes upon the drum-like extension E' after the glue has slightly set, and this drum is preferably very slightly smaller than the interior of a tube which would fit over the 65 grooved sleeves or cylinders, and is long enough to hold the tube straight until the setting of the glue leaves no danger or departure from rectilineal form. Usually the 70 formed tube is rotated and advanced by 75 oblique winding bolts J, without novelty. In some instances I omit alternate shafts C, and their sleeves and supply their places by fixed cylindrical segments K, Fig. 6, beyond the general peripheral surface of which 80 the remaining sleeves project very slightly. I also sometimes place upon the central shaft B', Fig. 8, a sleeve or cylinder D' similar to 85 those already described, and pass strips I' inward between the sleeves D and allow 90 them to wind upon this inner cylinder or mandrel forming a smaller tube; and it is 95 100 105 110

quite possible to wind simultaneously the larger and smaller tubes. Whether the smaller tube is to be formed alone or the two are to be wound simultaneously, the right end of the segment E' (when this is used) is omitted and the segment is supported entirely from its left end, which is rigidly secured to the member E. Since the rotary shafts are all supported at two widely separated points in the frame A and are held properly spaced by the member E, their resistance to flexure is practically sufficient to maintain suitable alignment of the projecting parts.

15. What I claim is:

1. A mandrel, for spirally wound tube making, having as its outer portion a series of parallel spirally grooved cylinders equidistant externally from a common central axis.
2. A mandrel, for spirally wound tube making, having as its outer portion a series of parallel spirally grooved cylinders equidistant externally from a common central axis combined with means for rotating all the cylinders at the same rate in the same direction.
25. 3. The combination with a series of equal

spirally grooved parallel cylinders equidistant from a central axis, of means for rotating all the cylinders in the same direction at the same rate, and means for externally engaging and imparting rotary force to a tube wound about said cylinders.

4. The combination with a spirally grooved central mandrel, of a series of spirally grooved cylinders equidistant from the mandrel, parallel thereto and spaced apart to allow tube stock to pass to said mandrel, and means for rotating the mandrel and cylinders each upon its own axis.

5. In a mandrel for spirally wound tube making, the combination with a series of parallel spirally grooved or corrugated cylinders equidistant from a central axis, of a cylindrical drum adapted in size and position to receive a tube formed about said cylinders and moved longitudinally therefrom, and means for rotating all the cylinders in the same direction and at the same speed.

In testimony whereof I affix my signature in presence of two witnesses.

CHARLES FRANCIS JENKINS.
